UNITED STATES PATENT OFFICE.

CHARLES L. HENDERSON, OF NEENAH, WISCONSIN, ASSIGNOR TO PAPER PATENTS COMPANY, OF NEENAH, WISCONSIN, A CORPORATION OF WISCONSIN.

PAPER-MAKING MACHINERY.

Application filed April 17, 1925. Serial No. 23,765.

This invention relates to machinery for making paper, but more particularly to screens or strainers for the purpose of removing from the pulp, all lumps or undigested stock which would show in the paper if permitted to remain. This screen is of the flat type in which the stock is caused to pass through slotted plates by the vibration of diaphragms.

10 The primary object of my invention is to produce a simple and effective mechanism for operating the diaphragm which will increase the capacity of the screen, reduce the cost of construction and maintenance, 15 and consume less power than existing mechanisms of a similar character.

Further objects are to provide noiseless operation, to permit repairs to the screen while in operation, to eliminate friction and 20 the necessity for oiling parts, to reduce the amount of space required, to eliminate pulleys and belts, to provide a variable stroke independent of the speed, to provide more 25 flexibility in arrangement, to provide balance of the moving parts, and in general to provide a new and improved screen construction.

The many other objects and advantages of my improved screen or strainer will be better understood by reference to the following specification when considered in connection with the accompanying drawings illustrating a selected embodiment thereof, in which:—

Fig. 1 is a longitudinal section of a screen embodying the principles of my invention.

Fig. 2 is a bottom plan view of the diaphragm operating mechanism shown in Fig. 1.

Fig. 3 is a transverse section on the line 40 3—3 of Fig. 1. Fig. 4 is a diagrammatical view of the electrical connections of the operating solenoid, and

Fig. 5 is a fragmentary plan view.

Referring to the drawings, a series of 45 slotted screen plates 10 are supported in the screen frame 11, above the vibrating diaphragm 12. The particular construction of this frame forms no part of the present invention, but in this embodiment comprises 50 an upper receptacle 13 supported by a central frame 14 on which the plates 10 rest, and a lower section 15. The diaphragm 12 of rubber or other suitable material, is held

between the central and lower sections. Any 55 suitable form of base or support for the screen may be provided. The plates extend between the cross pieces 16 and 16' of the central frame, and between these pieces and the end pieces 17, and are preferably 60 slotted as at 18. The spacing and width of these slots may be varied but generally they are formed narrower at the top than at the bottom to avoid choking. The intermediate cross pieces 16' are preferably 65 made narrower than the others to permit the vibrating of the diaphragms in the manner which will be presently described. A single diaphragm preferably extends under the entire screen but this diaphragm acts as 70 a series of separate diaphragms 19 in view of the fact that the same is held between the cross pieces 16 and corresponding pieces 20 of the lower frame as at 21. The screen frame is generally constructed of wood 75 though any other suitable material may obviously be used.

The mechanism for vibrating the diaphragm 19 will now be described. Plates as 30 and 31 are preferably placed on opposite 80 sides of each of these diaphragms and secured together by bolts as 32 which in the present embodiment also attach thereto brackets 33. Downwardly projecting arms 34 are provided on each of these brackets 85 and pivot or crank pins as 35 have their opposite ends supported in these arms. Adjoining diaphragms are operated by substantially T-shaped crank members as 36, two being preferably provided at each position. 90 Each of these members has bearings as 37, formed at the extremities of the cross arm and the corresponding crank pins 35 extend therethrough. A casting as 38 supports an electromagnetic device, in this instance a 95 solenoid 39, and this casting is provided at each of the ends with oppositely disposed bearings 40 which support a pivot pin 41. This pin passes through bearings 42 in the T-shaped crank members and such bearings 100 are located substantially at the intersection of the cross arm with the depending stem of the member. Similar bearings 43 are provided at the lower extremities of the depending stems and crank pins 44 are supported in these bearings. Rods 45 connect 105 these crank pins with the cores 47 of the

solenoid and such rods are provided at their outer ends with bearings as 46 through which the crank pins pass. The details of the solenoid are not illustrated as these devices 5 are well known.

The screened stock leaves the device through passages as 48 which communicate with the usual outlet pipe or trough. The stock which has failed to pass through the 10 plates is permitted to flow off the strainer at intervals, or is washed off.

A suitable system of electrical connections for the operation of the solenoid is diagrammatically illustrated in Fig. 4. Here any 15 suitable motor 50 drives an alternating current generator 51 wound to deliver current at a low frequency, for example, 10 to 15 cycles per second. This low frequency A. C. current passes through wiring 52 to a suitable 20 rectifier 53 which thus delivers a pulsating current to the solenoid. The cores of the solenoid preferably move approximately a small fraction of an inch, say $\frac{1}{8}$ th for each pulsation of the current.

25 The diaphragms 19 are operated by the solenoid in the following manner:—As one of the rods 45 is forced outwardly, the depending stems of the corresponding pair of T-shaped members are caused to rock about the axis of the pivot 41, imparting a similar 30 rocking movement to the cross pieces of such members. This forces the corresponding outer diaphragm upwardly and draws the inner diaphragm downwardly. The flexing 35 of the diaphragms returns the parts to normal position when the current impulse ceases, or if desired any suitable spring may be employed for that purpose. The same diaphragm action is provided by the other 40 of the solenoid rods. It will thus be observed that one diaphragm of each pair will be moving upwardly, while the other is moving downwardly and since the rods 45 are simultaneously reciprocated in opposite 45 directions, oppositely disposed diaphragms are actuated simultaneously in the same direction whereby a balanced effect is obtained which greatly reduces the strain to which the screener is otherwise subjected.

50 It will be observed that the members 16 form, in effect, partitions between the separate compartments of the apparatus. Each compartment is thus provided with an upper screen and a lower separate diaphragm. 55 By using separate screen compartments the diaphragms in adjacent compartments may be reciprocated in opposite directions so that a proper balanced action may be secured.

60 In the present invention waste of power is eliminated. The operation is substantially noiseless and repairs may readily be made while the screen is in operation. The cost of construction and maintenance is materially 65 reduced. All parts are in perfect balance,

and more flexibility in arrangement is possible. The stroke may be varied independently of the speed.

I am aware that the form and arrangement or parts may be considerably varied 70 without departing from the spirit of my invention and I reserve the right to make all such as fairly fall within the scope of the following claims.

I claim as my invention:

1. In a machine of the class described, the combination with a diaphragm, of means for imparting a vibratory movement to said diaphragm including an electro-magnetic device coating with said diaphragm and 80 means for energizing said device.

2. In a device of the class described, the combination with a screen and a diaphragm for forcing paper stock through said screen, of means for imparting a vibratory movement to said diaphragm including an electro-magnet having a reciprocating core connected to said diaphragm, and means for supplying pulsating current to the electro- 85 magnet.

3. A device for screening paper stock comprising a slotted plate, a diaphragm disposed opposite said plate for forcing the stock through the slots in said plate, and means for imparting a vibratory movement 95 to said diaphragm including a solenoid having a core connected to said diaphragm and means for supplying pulsating current to the solenoid.

4. In a device of the class described, a 100 screen for straining the paper stock, a vibratory diaphragm opposite said screen for drawing the stock through said screen, and means for actuating said diaphragm including a solenoid and a core connected to said 105 diaphragm and actuated by said solenoid.

5. In a device of the class described, a screen for straining the paper stock, a vibratory diaphragm disposed opposite said screen for drawing portions of the stock 110 through said screen, and means for actuating said diaphragm including a solenoid, a reciprocating core for said solenoid, and a crank arm connecting said core with said diaphragm.

6. In a device of the class described, a screen for straining paper stock, a vibratory diaphragm disposed opposite said screen for drawing a portion of the stock through said screen, and means for actuating said diaphragm including a solenoid having its axis substantially parallel to the plane of the diaphragm, a core within said solenoid and movable thereby longitudinally of said axis, and a bell crank connecting said armature 120 with said diaphragm.

7. In a device of the class described, the combination of a screen, a pair of diaphragms, each disposed opposite a different portion of said screen, means for simul- 130

taneously imparting movement in the same direction to said pair of diaphragms comprising a pair of operating rods disposed substantially in longitudinal alignment relative to each other, and means for imparting movement to said rods simultaneously in opposite directions.

8. In a device of the class described, a screen for straining paper stock, two pairs 10 of diaphragms each diaphragm being disposed opposite a different portion of said screen, bars connecting said diaphragms of each pair, said bars being pivoted intermediate their points of connection with said 15 diaphragms and having an arm extending therefrom, a separate rod connected at the end to each of said arms and means for imparting simultaneous movement to said rod in opposite directions.
9. In a device of the class described, a screen for straining the paper stock, and means for drawing a portion of the stock through said screen including a pair of diaphragms each disposed opposite a different 20 portion of said screen, a bar connecting said diaphragms and pivotally supported midway between the points of connection, an arm extending laterally from said bar at said midway point and forming with said 25 bar a substantially T-shaped member, and

a solenoid coating with the outer extremity of said arm to impart a rocking movement to said member and thereby cause a vibratory action to be transmitted to said diaphragms.

10. In a device of the class described, the combination of a screen, a pair of diaphragms, each disposed opposite a different portion of said screen, means for simultaneously imparting movement in the same direction to said pair of diaphragms comprising a pair of bell cranks pivotally mounted intermediate their respective arms on a fixed portion of the device, and each having one arm pivotally connected respectively to one 40 of said screens, a pair of oppositely disposed and substantially longitudinally aligned operating rods, each having one end pivotally connected respectively to the other arm of said bell cranks, and means for effecting 45 longitudinal movement of said rods simultaneously in opposite directions.

11. In a device of the class described, a screen for straining paper stock, a plurality 50 of diaphragms for aiding the straining operation, and means for actuating said diaphragms comprising a pair of operating rods reciprocatingly actuated simultaneously in opposite directions.

CHARLES L. HENDERSON.
